UNITED STATES PATENT OFFICE.

CHARLES E. GODLEY, OF DETROIT, MICHIGAN.

DESIGN FOR A LAMP.

56,098.

Specification for Design.

Patented Aug. 17, 1920.

Application filed April 16, 1920. Serial No. 374,482. Term of patent 14 years.

To all whom it may concern:

Be it known that I, CHARLES E. GODLEY, a citizen of the United States, and residing at Detroit, in the county of Wayne and State of Michigan, have invented a new, original, and ornamental Design for Lamps, of which the following is a specification, reference being had to the accompanying drawing, forming part thereof.

Figure 1 in the drawing is a perspective and Fig. 2 is a side elevation of a lamp embodying my new design.

The lamp body 1 is cup-shaped and the lens ring 2 is secured thereto by means of a polished locking ring 3, the lens ring being provided with a semi-cylindrical bead 4, also polished. The remainder of the exterior surfaces of the lamp body and lens ring are dull.

I claim:

The ornamental design for a lamp, substantially as shown and described.

CHARLES E. GODLEY.
